PROPELLER CUFF

Adolph E. Felt, Milwaukee, Wis., assignor to A. O. Smith Corporation, Milwaukee, Wis., a corporation of New York

Application August 1, 1951, Serial No. 239,699

3 Claims. (Cl. 170—159)

This invention relates to propeller blades and more particularly to a new and improved shank fairing or cuff for the same.

An object of the present invention is to provide a light-weight and structurally simple fairing or cuff which may be conveniently attached to the propeller blade without any projecting joints or connections which would adversely affect the aerodynamic properties of the blade.

Another object is to provide an improved propeller blade cuff which may be conveniently formed of two separate hollow members which are independently mounted on the blade and spaced therefrom, and from each other, by an intermediate plastic-like substance.

Still another object is to provide a flexible cuff for a propeller blade which may be conformed to fit varying airfoil contours caused by irregularities in construction of basically similar blades.

A further object is to provide a cuff for a propeller blade which will not materially increase the thickness of the blade and result in a loss of aerodynamic properties.

An airplane blade generally is comprised of a circular shank which gradually flares into the flatter airfoil shape of the blade. The shank, being constructed with this circular, non-streamlined form, provides adequate strength for the blade and facilitates mounting thereof, but does not create a stream of air adjacent the hub portion of the propeller during rotation of the blade.

It has been found that the efficiency of the blade can be materially increased and, where the propeller driving engine has cooling surfaces in the wake of the propeller, the cooling of the engine may be greatly improved by providing the unstreamlined shank portion of the blade with an airfoil fairing or cuff to create an air stream in the area surrounding the axis of rotation.

The present invention is directed to a propeller cuff for use with a propeller blade of airfoil section. The cuff comprises a pair of hollow airfoil-shaped light-weight metal halves or members which are integrally formed and independently mounted in chordwise spaced relation on the respective leading and trailing portions of the shank of the blade to complement the airfoil contour of the blade. The cuff serves as a fan to create an air stream adjacent the axis of rotation of the propeller and to direct this stream over the engine.

A resilient plastic material, such as rubber, is disposed between the blade and the adjacent surfaces of the spaced cuff halves. By vulcanizing this intermediate rubber layer the cuff halves are effectively bonded to the blade to provide a light-weight airfoil cuff with no projecting joints or attachments on the airfoil surfaces.

In the drawings:

Figure 1 is a top plan view of the shank of a propeller blade showing the cuff of the invention and with parts broken away and sectioned;

Fig. 2 is a section taken on line 2—2 of Figure 1;

Fig. 3 is a section taken on line 3—3 of Figure 1;

Fig. 4 is a section taken on line 4—4 of Figure 1;

Fig. 5 is a section taken on line 5—5 of Fig. 1; and

Fig. 6 is a detail section on the line 6—6 of Fig. 2.

Referring to the drawings, there is shown a light-weight flexible propeller cuff or fairing 1 carried on the shank portion 2 of a propeller blade to provide the shank with an airfoil contour complementary to the airfoil contour of the blade.

2

Cuff 1 comprises a pair of airfoil-shaped hollow members or halves, one of which is a trailing edge member 3 and the other, a leading edge member 4.

Cuff members 3 and 4 are spaced from each other in chordwise relation on the periphery of the blade and are independently mounted on the respective trailing and leading edge portions of the shank of the blade with which they correspond.

The trailing edge and the leading edge of the respective cuff members 3 and 4 are in alignment with the respective leading and trailing edges of the blade and both the trailing and leading edges of members 3 and 4 may be swept back in the direction of the trailing edge of the blade to provide clearance for movement of the blade during pitch control.

As cuff members 3 and 4 of the present invention are of substantially similar structure and are similarly attached to the respective trailing edge portion and leading edge portion of the blade, the following description is directed to the structure and attachment of only the trailing edge member 3.

Cuff member 3 comprises a lightweight alloy sheath 5 having a generally V-shaped cross section which is integrally formed from a single sheet of metal. Sheath 5 includes a camber airfoil surface 6 and a face airfoil surface 7 which are designed to complement the airfoil contour of the blade.

The generally curved inner edges 8 and 9 respectively of the camber airfoil 6 and the face airfoil 7 of sheath 5 are substantially tangent to the respective camber surface 10 and face surface 11 of the shank 2 and are spaced thereon outwardly in a chordwise direction from the longitudinal center line of said surfaces 10 and 11.

The outboard edge 12 of the sheath is aligned with the portion of the peripheral welded joint 13 adjacent the trailing edge of the blade. Welded joint 13 serves to secure shank 2 to the central portion of the blade and extends completely around the blade.

The inboard end of sheath 5 of cuff member 3 is closed 40 by a generally triangular closure plate 14 having a base formed complementary to shank 2. Closure plate 14 is preferably constructed of lightweight sheet alloy material and is provided with a flange 15 which extends substantially around the entire perimeter of plate 14 inwardly toward the propeller hub.

Flange 15 is in contacting relation with the inner surface of the respective camber airfoil 6 and face airfoil 7 of sheath 5 and is secured thereto by stitch weld 16. The base portion of flange 15 of closure plate 14 complements shank 2 and is adapted to fit within a circumferential groove 17 formed in the annular split ring 18 which encircles shank 2. Flange 15 is secured to ring 18 by suitable stitch welds.

At the base end of each side portion of flange 15 a short section of the flange is omitted for insertion of the ring 18 and the assembly is clamped to the shank by a split retaining ring 19 which encircles the ring 18 on shank 2 and is adapted to fit over the curved base portion of flange 15.

Split retaining ring 19 is tightened around shank 2, by a clamping screw 20, thereby securing the closure plate 14 to the shank. An annular seal 21 encircles shank 2 and is disposed beneath the ring 18. Seal 21 is compressed between the ring 18 and the shank when the split ring 19 is tightened.

A snap button 22 is inserted in a suitable opening in the web of closure plate 14 to permit access to the hollow interior of cuff member 3 for removal of foreign matter or for the installation of electrical de-icing systems therein.

A yoke support 23 is disposed within the cuff member 3 and extends between the face airfoil 7 and camber

airfoil 6 of sheath 5. The support 23 is spaced outwardly from the inboard closure member 24 and is cushioned therefrom by rubber yoke pad 25. The support 23 prevents the airfoils 6 and 7 from spreading apart during rotation of the blade.

To provide a flexible means of attaching cuff members 3 to the shank of the blade and to prevent metal-to-metal contact between the cuff and the blade, a plurality of rubber or resilient plastic seals are interposed between the adjacent cuff and blade surfaces.

An outboard peripheral seal 26 overlaps the peripheral weld seam 13 and extends completely around the blade. Seal 26 serves to prevent metal-to-metal contact between the outboard edge 12 of sheath 5 and the underlying shank 2.

The outboard portion of sheath 5 partially overlaps seal 26 and the outboard edge 12 of the sheath abuts against a peripheral shoulder 27 formed in the outer surface of seal 26. The outboard portion of seal 26 tapers inwardly toward the blade to provide a smooth streamlined junction with the blade surface.

The portions of the outboard peripheral seal 26 overlapping the trailing and leading edges of the blade may be formed with an exterior slit 28 and a connecting, transversely extending, drainhole 29. Slit 28 and drainhole 29 provide a through passage between the interior of the hollow cuff member 3 and the atmosphere and serve as a drain for condensation and foreign matter which may accumulate within cuff member 3.

A camber seal 30 and a face seal 31, which are constructed of rubber or a plastic material, extend longitudinally along the respective camber surface 10 and face surface 11 of shank 2 and serve to prevent metal-to-metal contact between surfaces 10 and 11 and the respective tangential curved inner edges 8 and 9 of sheath 5.

The inboard extremities of both seals 30 and 31 abut against the annular seal 21, and the outboard extremities of seals 30 and 31 abut against the peripheral shoulder 27 of outboard seal 26.

The inner portions of face airfoil 7 and camber airfoil 6 of sheath 5 partially overlap the respective seals 30 and 31, and the generally curved inner edges 8 and 9 of the sheath abut against a complementary curved shoulder formed in the outer surface of each of the seals 30 and 31 to provide a clean unobstructed joint on both the camber and face surfaces of the blade.

The camber seal 30 and the face seal 31 may each be formed integrally or in a number of sections depending on convenience of manufacture. The portion of each seal 30 and 31 overlapping the longitudinal center line of the respective camber and face surfaces of the shank is formed with a minimum thickness, substantially less than the thickness of the outer portions of the seals 30 and 31 which underlap the respective sheath airfoils 6 and 7, thereby substantially maintaining the central blade thickness at a minimum and not adversely affecting the aerodynamic properties of the blade.

The propeller blade, together with the cuff of the present invention, is placed in a vulcanizing oven wherein the rubber seals 21, 26, 30 and 31 are cured or vulcanized to secure the cuff to the exterior surface of the blade.

The use of vulcanized rubber seals provides a light-weight flexible attachment of the cuff to the blade. Due to resonant vibrations set up in the blade during rotational operation, the attached cuff tends to breathe or bellow in and out. The flexible attachment of the invention permits the cuff to so breathe without danger of rupture or undue stress at the point of attachment.

In addition the cuff of the invention provides a smooth aerodynamic surface, there being no projecting joints, connections or other obstructions on the airfoil surface to adversely affect the aerodynamic properties of the blade.

Various embodiments of the invention may be employed within the scope of the following claims.

I claim:

1. In combination with a propeller blade of airfoil section, a cuff carried by said blade and comprising a pair of hollow cuff members mounted on the shank of the blade to complement the airfoil contour of said blade, each of said members being formed of a face surface and a camber surface joined together at their outward edges with the inner edges of the face and camber surfaces of each member disposed astride the shank and disposed generally tangentially to the face and camber surfaces of the shank, and with the inner edges of the face and camber surfaces of each member spaced in a chordwise direction from the longitudinal center line of the corresponding face and camber surfaces of the shank, each member having an open end portion facing inboardly of said blade, a closure for the open end portion of each member, reinforcing means disposed within each member and connecting the face and camber surfaces of said member to prevent said surfaces from spreading apart during rotational service of the blade, and bonding means for flexibly securing said members to the shank of said blade with said members being out of contact with said shank.

2. In combination with a propeller blade of airfoil section, a light-weight metal cuff carried by the shank of the blade to complement the airfoil contour of said blade and comprising a trailing edge member and a leading edge member, each of said members having a generally U-shaped cross section and formed with a face surface and a camber surface, said members being mounted on the shank with the face surface and camber surface of each member disposed astride said shank in a generally tangential relation to the corresponding camber and face surfaces of the shank and with the inner edges of the face and camber surfaces of each member spaced in a chordwise direction from the longitudinal center line of the corresponding camber and face surfaces of the shank, and a plastic material interposed between said members and the adjacent surface of the shank to prevent contact between said members and said shank surface and to bond the members to said blade surfaces.

3. In combination with a propeller blade of airfoil section, a light-weight metal cuff carried by the shank of the blade to complement the airfoil contour of the blade and comprising a pair of hollow cuff members, each of said members being formed of a face surface and a camber surface integrally joined at their outward edges with the inner edges of the face and camber surfaces of each member straddling the shank and disposed generally tangentially to the face and camber surfaces of the blade respectively and having the inner edges of the face and camber surfaces of one of said members spaced in a chordwise direction from the corresponding inner edges of the face and camber surfaces of the other member, a band of resilient material interposed between the outboard ends of said members and said blade, a second band of resilient material interposed between the inboard ends of said members and the shank of said blades, and a pair of resilient strips extending between said resilient bands along the face and camber surfaces of said shank and interposed between the inner edges of the face and camber surfaces of said members and said blade, said resilient material serving to flexibly bond the members to said blade.
